UNITED STATES PATENT OFFICE.

MARTIN B. MILLER, OF OMAHA, NEBRASKA.

AUTOMATIC CREAM-COOLER.

SPECIFICATION forming part of Letters Patent No. 700,148, dated May 13, 1902.

Application filed February 12, 1902. Serial No. 93,719. (No model.)

To all whom it may concern:

Be it known that I, MARTIN B. MILLER, residing at Omaha, in the county of Douglas and State of Nebraska, have invented certain 5 useful Improvements in Automatic Cream-Coolers; and I do hereby declare that the following is a full, clear, and exact description of the invention, such as will enable others skilled in the art to which it appertains to 10 make and use the same, reference being had to the accompanying drawings, which form a part of this specification.

This invention has relation to a new and novel improvement in automatic cream-coolers.

The object of my invention is to provide a tank adapted to contain cream and within which tank is to be held a cooling-coil adapted to be carried gently through the cream to 20 cool the same; and my invention embodies the combination of certain instrumentalities, as will be described more fully hereinafter and finally pointed out in the claims.

In the accompanying drawings I have shown 25 in Figure 1 a side elevation of an automatic cream-cooling tank embodying my invention. Fig. 2 shows a top view with portions removed. Fig. 3 shows a central sectional view, while Fig. 4 shows a detached detail disclosing 30 the arrangement of the cooling-coil and the connected float.

My invention embodies, essentially, a water-tight trough supported by means of the legs 22 and embracing the ends 11, the sides A, 35 and the bottom 3, as disclosed. Extending from this water-tight trough is a suitable stop-cock 4, as is disclosed in Figs. 1 and 3, located near the bottom, while preferably at the same end and above the stop-cock is an escape-pipe 5. This trough is adapted to contain a cream-holding receptacle or tank B, 40 preferably provided above with the outwardly-flared edges a, by means of which this tank is held within the trough A. This tank 45 is preferably flared inward, so that the bottom area is smaller than the upper end of the tank, as will be understood in referring to Fig. 3. Extending from the bottom of this tank B, adapted to contain the cream, is a suitable 50 stop-cock 10, so that this tank may be drained. Extending transversely across the top of the

trough is a central cover 7, to which are secured the lids 8, reinforced by means of the grates, as is clearly shown in Fig. 3. Located upon the central top portion 6 is a water-tank F, from which tank extends upward a pipe c, (shown in the top view in Fig. 2 and in a dotted elevation in Fig. 3,) this pipe being in open communication with the water-tank F, so that the water rising within the tank will 60 also rise within this connected tube or pipe c. From a point preferably opposite the intake-point of the tube or pipe c extends a siphon H, which siphon is also in open communication with this water-tank F, and this siphon 65 is directed into the lower water-tank A, as is disclosed in Fig. 1, where the dotted end of the siphon H is disclosed. Accordingly when the water rises within this upper tank and finds an escape through the siphon H 70 the siphon will be primed and so empty this upper water-tank F. This tank F is preferably round, though it may be of any suitable conformation, and held therein is a suitable float C of a predetermined lifting capacity, from 75 which project upward and thence downward the supporting-brackets b, so positioned that they extend upward over the edge of the water-tank F and downward through suitable openings within the coverings 6 and 8 almost to the 80 bottom of the cream-holding tank or receptacle B, as is clearly shown in Fig. 3. Below these brackets b are secured to the bars 12 12, which in turn are secured to the cooling-coil D, comprising a plurality of connected tubes of a length almost the length of the cream-holding receptacle and being coiled 85 from end to end, as is shown in Fig. 2. The capacity of the float C, which may be a copper tank or be composed of any other suitable material, is in excess of the work of the cooling-coil D and the brackets b. One end of this cooling-coil D is extended upward to provide the termination 13, as is shown more clearly in Fig. 4, while the remaining end 90 terminates in the gooseneck 14, which gooseneck is adapted to work within the tube c, as is shown in top view in Fig. 2 and in dotted lines in Fig. 3. Adjacent this water-tank F is positioned a suitable water-supply tank 18, 95 from which extends an elastic tubing 17—as an ordinary garden-hose, for instance—the end

of which is secured to the upward coil extension 13, which passes through a suitable opening within the top 6, as does also the gooseneck 14.

- 5 Now in the use of my cream-cooler the operation would be as follows: The cream to be cooled would be placed within the cream tank or receptacle. The cooling-water from the tank 18 would next be permitted to flow 10 through the tube 17, down the pipe 13, circulating through the coil D, and then passing upward and again downward through the gooseneck 14, emptying into the pipe or tube c. From this pipe c the water would readily 15 escape into the upper water-tank F, and as it rose in this tank it would rise within the siphon H, as well as raise the float C and the connected cooling-coil D, secured to the same by the brackets b. In gently rising through 20 the cream the cream would be gently agitated and cooled by the flowing water passing through the same, and this coil would rise upward a suitable height, determined by the overflow of the water through the siphon H. 25 As soon as the siphon H was started the water would flow out of the tank F, the siphon being made of a larger capacity than the intake water supply entering the tank F through the gooseneck 14, the instrumentalities being 30 so arranged that the coil D would descend at about the same rate of speed that it rose until the water-tank F was emptied. During the period of the siphoning it is of course understood the water-supply is continually entering this tank F through the pipe 17 and the coil, as has been described. Now as the tank F gradually filled up again the coil would be carried upward, so that this cooling-coil D is continually operated upward and downward 35 40 to be carried through the cream to cool the same. However, the water which was first made to circulate through the coil D to cool the cream and thence raise the coil would be still used, in that it would next fill the space between the trough and the cream-tank B, rising between the same until it found an outlet through the pipe 5. From this it will be noticed that the stream is used twice to cool the cream and, in addition, made to operate the 45 50 instrumentalities to raise and lower the coil. While I have described the water as being

drawn from the tank 18, it is of course understood that the tube 17 would be in connection with some suitable water-supply—as a city service, for instance. Now after the cream 55 has been sufficiently cooled the operator would open the stop-cock 10 and draw off the contents, so that the tank would be given a thorough cleansing. The coil D being but a simple tube it can be easily cleaned, and so, also, it 60 should be remembered that the tube 17 be placed in connection with a warm or hot water supply, so that, if desired, the cream or other batch within the receptacle or tank B could be raised in temperature, if that were 65 desired.

The device is neat and simple of construction, and the working effects are so arranged that they may be easily cleansed, and

Having thus described my said invention, 70 what I claim as new, and desire to secure by United States Letters Patent, is—

1. The combination with a suitable trough having an outlet, of a tank held within said trough, a water-receptacle above said tank, a 75 siphon extending from said receptacle and emptying into said trough, a float within said water-receptacle, a cooling-coil secured to said float, one end of said cooling-coil being in connection with a suitable intake, the remaining end connected to said water-receptacle.

2. The combination with a trough, of a tank held within said trough, an exit-pipe extending from said trough, a drain-cock secured to 85 said tank, a water-receptacle secured above said tank, a siphon extending from said water-receptacle and entering said trough, a cooling-coil within said tank both ends extending upward, one terminating in a gooseneck connected to said water-receptacle, the remaining end being in connection with the water-supply, and a float within said water-receptacle secured by means of brackets to said cooling-coil, all arranged substantially 90 95 as and for the purpose set forth.

Signed in the presence of two witnesses.

MARTIN B. MILLER.
